UNITED STATES PATENT OFFICE.

ROY BERCHEEN, OF FAYETTEVILLE, TENNESSEE.

ACETYLENE-GAS GENERATOR.

1,159,159.

Patented Nov. 2, 1915.

Application filed October 3, 1914. Serial No. 864,827.

To all whom it may concern:

Be it known that I, ROY BERCHEEN, a citizen of the United States, residing at Fayetteville, in the county of Lincoln and State 5 of Tennessee, have invented new and useful Improvements in Acetylene-Gas Generators, of which the following is a specification.

The invention relates to acetylene gas generators; and has for its object to provide a 10 generator of this character wherein the gasometer or bell is formed with a water displacer which serves to lift the water to the carbid holder or container which is of the collapsible type to allow it to be readily and 15 easily cleaned when the same is to be refilled with carbid, the gasometer or bell being of novel form to insure the perfect working of the generator.

Another object of the invention is the provision of a generator of this character 20 wherein the gas service pipe has one stretch thereof arranged within the water tank and is inclosed in a jacket so as to avoid the possibility of the sweating of the said stretch 25 of the pipe when the generator is in action, thus the said stretch of the pipe will be rendered perfectly dry at all times.

A further object of the invention is the provision of a generator of this character 30 wherein the service pipe has tapped therein a filter which removes all sediment or foreign matter from the gas flowing therethrough, the point of connection of the service pipe with the filter being above the bottom 35 of the latter, so that the sediment and foreign matter collected therein will not interfere with the free flowing of gas through the service pipe, thereby avoiding any possibility of the choking up of the 40 burners at the points of illumination of the gas from the service pipe.

A still further object of the invention is the provision of a generator of this character known generally as the floating gasometer type having a dip carbid container or holder possessing simplicity, efficiency and durability, also one which may be manufactured at a minimum expense.

With these and other objects in view, the 50 invention consists in the construction, combination and arrangement of parts as will be hereinafter fully described, illustrated in the accompanying drawing, and pointed out in the claims hereunto appended.

55 In the drawing:—Figure 1 is a vertical longitudinal sectional view through the gen-

erator constructed in accordance with the invention; Fig. 2 is a perspective view of the collapsible carbid holder or container.

Similar reference characters indicate corresponding parts throughout the several views in the drawing.

Referring to the drawing in detail, the generator comprises an outer cylindrical water tank 5, which is open at its upper end 6 opposite the bottom 6 thereof and has arranged therein an inner cylindrical water tank 7 which is centrally disposed and rises from the bottom 6 within the said outer tank to form a water space 8 concentrically about 70 the said inner tank in which works the cylindrical side wall of a vertically movable gasometer or bell 9, the major portion of which is of uniform cross sectional size, while the remaining upper portion is contracted as at 75 10 and has an upper open end 11. The top 12 of the gasometer or bell is extended within the contracted portion 10 and has rising centrally therefrom a column 13 forming between it and the contracted wall 10 a water space 14 which extends concentrically about 80 the column 13. Depending from the top 12 of the bell or gasometer 9 is the extended tubular portion of a hollow cylindrical float 16 forming a water displacer working within 85 the inner water tank 7 for lifting the water into the column on the lowering of the gasometer or bell 9 within the outer water tank 5 of the generator. Detachably telescoped within the upper open end of the contracted portion 10 of the gasometer or bell 9 is an inverted cup-shaped cap 17 which is formed with a depending inner cylindrical flange 18, which is fixed to the top of the said cap 17 90 centrally thereof and is adapted to telescope 95 over the upper end of the column 13, so as to extend within the water space 14 concentrically about the column 13. The water when placed within the said space 14 acts as a water seal between the column 13 and the flange 18 on the cap while the water when placed within the space 18 serves as a water seal between the bell or gasometer 9 and the inner water tank 7, the tubular portion 15 being formed with a series of perforations 19 100 to permit the passage of gas from the space above the water displacer or float 16 into the upper portion of the bell or gasometer 9 above the water level therein.

Removably fitted within the central opening or bore in the water displacer or float 16 110 is a carbid container or holder comprising a

cylindrical body 20 having an inturned annular flange 21 at its lower edge and in this body is slidably fitted a cup-shaped bottom section 22, the same being formed with an 5 outturned annular flange 23 at its upper free edge to engage and rest upon the flange 21 on the body 20, thus the said carbide holder can be collapsed or extended, thereby enabling the convenient and easy cleaning of 10 the same when refilling it with a charge of carbide. Swingly connected to the body 20 is a hand-bail 24 which permits the convenient removal of the carbide container or holder from the generator or the placing of 15 the same therein. Rising centrally from the bottom section 22 is a reticulated or foraminous tube 25 which permits the entrance of water from the inner tank 7 on the lifting thereof by the water displacer or float 16 20 into the carbide container or holder, so that the carbide therein will be commingled with the water for the production of gas which fills the column 13 and is discharged through the perforations 19 into the bell or gasometer 25 which rises under the pressure thereof.

Mounted on the outer side of the body 20 of the carbide container or holder are bearings 26 which engage with the upper end of the float 16 for the holding of the carbide 30 container or holder within the central opening or bore therein.

Mounted exteriorly on the contracted portion 10 of the gasometer or bell 9 are reversely disposed hooks 27, while mounted on 35 the top of the cap is a bail 28 forming a handle having laterally extended ends 29 which serve as keepers to engage the hook 27 and thereby lock the cap in position for closing the upper open end of the gasometer 40 or bell. Tapped centrally in the top of the cap 17 is a valve or blow-off cock 30, while rising from the said top of the cap near the marginal or peripheral edge thereof is a safety spout 31, which is of the ordinary 45 well known construction.

Extending from the outer tank 5 is a water drain pipe 32 and likewise extending from the inner tank 7 through the outer tank 5 is a water drain pipe 33, so that the 50 water in both of these tanks can be readily drained therefrom as the occasion may require. Rising within the water space 8 between the outer and inner tanks 5 and 7 is a vertical stretch of a gas service pipe 34, 55 which is held fixed in any suitable manner and is extended through the outer tank 5 without the same and has connection with a gas filter 35 at a point above the lower end thereof which serves to collect all sediment 60 and foreign matter, and by reason of the

point of connection of the pipe 34 with the said filter 35 the service pipe will be prevented from choking or stopping up. The gas passing through the filter 35 is distributed to any desirable point in the usual well 65 known manner for illuminating purposes.

Surrounding the vertical stretch of the service pipe 3 and within the water space 8 is a tubular jacket 36, which is spaced from the said pipe and is closed at opposite ends 70 so as to prevent the sweating of the vertical portion of the said pipe 34 and thereby maintain the same constantly dry.

From the foregoing it is thought that the construction and manner of operation of the 75 device will be clearly understood, and therefore a more extended explanation has been omitted.

What is claimed is:—

1. A generator of the class described comprising an outer water tank, an inner water tank therein rising from its bottom, a gas bell working between the outer and inner water tanks and having a contracted upper portion, a column rising from the top of the 85 bell centrally within the contracted portion, a water float depending from and centrally within the bell and working within the inner water tank to displace the water into the said column, a carbide holder removably fitted within the upper portion of the float in alignment with the column and a removable cap fastened to the contracted portion of the bell for closing the column and the said contracted portion. 95

2. A generator of the class described comprising an outer water tank, an inner water tank therein rising from its bottom, a gas bell working between the outer and inner water tanks and having a contracted upper 100 portion, a column rising from the top of the bell centrally within the contracted portion, a water float depending from and centrally within the bell and working within the inner water tank to displace the water into the 105 said column, a carbide holder removably fitted within the upper portion of the float in alignment with the column, a removable cap fastened to the contracted portion of the bell for closing the column and the said contracted portion, and a service pipe having a stretch thereof extended upwardly within the space between the inner and outer water tanks. 110

In testimony whereof I affix my signature 115 in presence of two witnesses.

ROY BERCHEEN.
